UNITED STATES PATENT OFFICE.

ISAAC H. GARSON, OF NEW YORK, N. Y.

VENDING-MACHINE.

No. 893,247.

Specification of Letters Patent.

Patented June 30, 1908.

Application filed April 4, 1907. Serial No. 366,245.

To all whom it may concern:

Be it known that I, ISAAC H. GARSON, a citizen of the United States, residing at New York, in the county of New York and State of New York, have invented a new and useful Vending-Machine, of which the following is a specification.

This invention relates to an improvement in vending machines of the type adapted to vend cigars and analogous articles, and particularly to machines of the character of that described in Patent No. 842143, granted to me Jan. 22, 1907.

The mechanisms of machines of this character is of necessity delicate, and it has been found in practice that when the machine is subjected to rough treatment, such as an improper series of operations of the handle in rapid succession, the machine is liable to injury.

It is one of the objects of this invention to provide means for preventing such operation and thereby prevent injury to the machine.

Another object is to provide means for preventing the breakage of cigars and the delivery of an excessive number of cigars through an improper manipulation of the handle.

With these and other objects in view, the invention consists in certain constructions and combinations which will be hereinafter fully described and then specifically set forth in the claims hereunto appended.

In the accompanying drawings which form a part of this specification and in which like characters of reference indicate the same parts, Figure 1 is a sectional elevation of a device constructed in accordance with the invention, Fig. 2 is a plan view of the structure shown in Fig. 1, Fig. 3 is a sectional elevation through the cigar delivering mechanism, Fig. 4 is a view illustrating generally the coin chutes and coöperating mechanism, Fig. 5 is a view illustrating the coin receiving receptacles and connections, Fig. 6 is a view of a portion of the coin releasing mechanism, Fig. 7 is a detail view of the retarding cylinder for preventing excessive speed of the device, Figs. 8 to 11 inclusive are detail views illustrating the operating means for the delivering device and the repeating mechanism.

In the device selected to illustrate the invention, 1 indicates a casing provided with transparent panels 2. The lower part of the casing is composed of a box 4 separated from

the upper part by a partition provided with an aperture 6 within which is fitted a hopper 7 arranged to enter a cigar box or receptacle 8 from which the bottom has been previously removed.

The bottom of the hopper 7 is inclined from its ends toward its center where it is provided with an elongated aperture 12 beneath which operates a sectional carrier 13 which is mounted on a sleeve 14 revolubly fitted over a shaft 15, the periphery of the carrier 13 being provided with a series of pockets for the reception of the cigars from the hopper.

Rollers 17 are fitted in the walls of the pockets to prevent injury to the cigars entering the same and a roller 17^a located on the adjacent edge of the hopper is adapted to prevent injury to the cigars when they are delivered. A drawer 18 located at one side of the rotatable carrier 13 is adapted to receive the cigars delivered by the carrier, and this drawer may be withdrawn from the casing by the purchaser when one or more cigars have been delivered thereto by the carrier.

Agitating devices consisting of curved fingers 19 are provided for the purpose of causing the cigars to fall from the hopper into the pockets of the carrier, these fingers being mounted on a shaft 20 and operating through slots 21—21 formed in the bottom of the hopper.

Between the sections of the carrier 13 are arranged arms 22—22 which are each provided with a slot 23 embracing the sleeve 14, the upper end of the arms being arranged to be engaged by cigars successively delivered by the carrier 13. The opposite ends of these arms are connected to an arm 24 fixed to a shaft 25, to the opposite end of which an arm 26 is fixed. This arm 26 carries a pin 27 to which is attached a link 28 connected to an arm 29 mounted on a shaft 30 which carries two arms 31 and 32. A coin chute 33 is mounted above the arm 31 and discharges into a coin receptacle 34 mounted on a lever 35, the receptacle being open on one side and provided with a detent 36 which operates to retain the coin therein until the arm 31 is elevated and effects the ejection of the coin sidewise from the receptacle. A counterweight 37 mounted on the lever 35 effects the return of the lever to its normal position after the coin has been ejected from the receptacle. The coin-actuated member 38 is similarly provided with a receptacle 39

arranged to normally occupy a position below a chute 40, the arm 32 on the shaft, when actuated, operating in a manner similar to the arm 31 to eject the coin and permit the 5 return of the lever 38 to its normal position through the agency of the weight 41. The lever 38 is provided with an offset lug 38^a so arranged as to coöperate with the adjacent member 35 to simultaneously actuate the 10 latter when the member 38 is depressed. A link 42 connects the member 35 and an arm 43 fixed on a shaft 44 which carries a curved arm 45 normally operating to keep a lateral projection 46 of a pawl 47 out of contact with 15 a ratchet wheel 48 fast on the sleeve 14 before referred to. The pawl 47 is mounted on one end of a lever 49 fast on the shaft 15 before referred to. Depression of the member 35 operates through its connections to 20 rock the shaft 44, thereby depressing the arm 45 and permitting the pawl 47 to engage and operate the ratchet wheel 48 and consequently the carrier 13. When the member 35 is depressed, its connection with the member 38 25 and its connections produces the same result.

To the coin - actuated member 38 is attached a link 54 which forms a connection with a pivoted detent 55 the free end of which is provided with a projection 56 which 30 is arranged to engage the peripheral notches or recesses 57 which are formed in the disk 58, the latter being revolvably mounted on the operating shaft 15 and provided with a series of equi-distantly spaced projections 59 35 which are arranged to coöperate with a detent 60 which is pivoted to a relatively fixed portion of the machine and is operated under the yielding action of the spring 61, that portion of the detent which coöperates 40 with the projections of the disk 58 being provided with oppositely inclined surfaces for properly positioning the said disk at its different positions of rotation. The disk 58 is also provided with a series of projections 62 45 which coöperate with a pawl 63 while the latter occupies a predetermined position to positively prevent rotation of the said disk, and as this pawl 63 is fixed to the rock shaft 64 which is connected by the arm 65 to the 50 pin 27 of the operating arm 26, the said pawl will be disengaged from the projections of the disk 58 to permit rotation of the latter each time the arms 22 are operated by a cigar while being discharged from the carrier, and unless there is a cigar to be discharged by the carrier, the pawl 63 will 55 lock the disk from rotation. When the detent 55 has been disengaged from its corresponding notch 57 in the disk 58 and the latter has been rotated, the projection of the 60 detent will ride upon the periphery of the disk, and this will retain the members 38 and 35 depressed, and through the link 42 which is connected to the latter, the controlling arm 65 45 will be depressed and thereby permitting

the pawl 47 to coöperate with the ratchet 48 to actuate the latter.

To the operating shaft 15 is fixed an arm 66 to one end of which is attached the spiral spring 67, the opposite end of the said arm 70 being arranged to coöperate with a pin 68 to which the opposite end of the spring 67 is attached and which is fixed to an arm 69, the latter being rotatably mounted on the shaft 15 and provided with a pawl 70 which is arranged to coöperate with projections 62 of the disk 58 to actuate the latter, the spring 67 forming a yielding connection between the operating shaft 15 and the pawl arm 69 to cause the disk to be actuated when the operating shaft is rotated while the detent 55 is unlocked from the disk, it being obvious that the operation of the shaft 15 while the disk 58 is locked by the detent 55 would fail to operate the disk, as the spring 67 forms a yielding connection between the shaft and the pawl arm 69 and would permit the latter to remain stationary while the arm 66 which is fixed to the operating shaft disengages from the pin 68.

For the purpose of returning the operating shaft 15 to its normal position, a spring 71 may be employed. To the sleeve 14 is fixed a ratchet 72 with which coöperates a roller 73 mounted on a lever 74 which is held to its work by a spring 75. This lever when operated by the rotation of the ratchet 72 will, through its connections, rock the shaft 20 carrying the fingers 19—19 and thus agitate the cigars in the hopper and cause them to fall into position to be delivered by the carrier 13.

The mechanism so far described is like that in the patent above referred to and reference is made thereto for a full disclosure. A more detailed description of this part of the machine, being unnecessary to a full understanding of the present invention, is omitted in the interest of brevity and clearness.

Means for retarding the movement of the operating means is provided and this means may vary widely in structure.

The retarding means might be in operation during movements of the operating means in opposite directions, and the retarding means might be continuously connected with the operating means, and the latter continuously connected with the delivery device. In the best constructions, however, the retarding means will be continuously connected with the operating means and the latter will be intermittently connected with the delivery device, the retarding means operating during a movement of the operating means in one direction. As shown, retarding means consisting of a fluid pressure brake is employed for this purpose. This brake consists of a cylinder 90 provided with a lug 91 attached to one end of the lever 49 before referred to, this lever being fast on the operating shaft 130

15. A piston 92 works within the cylinder and this piston is provided with a series of holes 93 extending therethrough. A rod 94 is fast to the piston 92, extends through a 5 suitable head 95 fitted to one end of the cylinder, and its outer end is secured to a stationary post 96 mounted on the frame of the machine. The piston is provided with a flexible valve 97 arranged to close the holes 10 93 during a relative movement of the cylinder and piston in one direction, and to open them during a movement in the opposite direction. The cylinder is filled with a suitable slow flowing fluid. The fit of the piston in 15 the bore of the cylinder is such that when the valve 97 is closed, a relative movement of the cylinder and piston in one direction causes the fluid to slowly pass in a thin film between the periphery of the piston and the wall of 20 the cylinder. A movement in the opposite direction causes the valve to open and permits the fluid to readily flow through the holes 93. The connections are such that the retarding means comes into operation when 25 the delicate mechanism of the machine is brought into action and when the carrier 13 is rotated to deliver a cigar, thus preventing injury to the machine and the possibility of the delivery of an excessive number of cigars 30 through improper manipulation of the operating means.

Changes and variations may be made in the structure by which the invention is carried into effect. The invention, therefore, is 35 not to be restricted to the precise details of the structure shown and described.

What is claimed is:

1. In a vending machine, the combination with a receptacle for the articles to be vended, 40 of a delivery device coöperatively arranged therewith, operating means capable of being connected and disconnected from the delivery device for actuating the latter, a retarding device connected with the operating 45 means, and repeating mechanism for maintaining the operating means and the delivery device in operative connection to permit the latter to be successively operated a predetermined number of times.

2. In a vending machine, the combination with a receptacle for the articles to be vended, 50 of a delivery device coöperatively arranged therewith, of operating means for the delivery device, a retarding device connected with the operating means, and separately released devices coöperating with the operating means and controlled by the articles discharged for causing a different number of operations of the delivery device.

3. In a vending machine, the combination

with a receptacle for the articles to be vended, of a delivery device coöperatively arranged therewith, of operating means capable of being connected and disconnected from the delivery device, a retarding device connected with the operating means, a device for connecting the operating means to the delivery device to cause a single operation of the latter, and a repeating device capable of maintaining the connection 65 between the operating means and the delivery device to permit a predetermined number of operations of the latter.

4. In a vending machine, the combination with a receptacle for the articles to be vended, 70 of a delivery device coöperatively arranged therewith, of operating means for the delivery device, a retarding device connected with the operating means, a controlling device for connecting and disconnecting the operating means and the delivery device, a member operating upon the controlling means to establish operative connections between the operating means and the delivery device, and means controlled 75 by the discharge of an article from the latter for resetting the controlling means.

5. In a vending machine, the combination with a receptacle for the articles to be vended, 80 of an operating shaft carrying an actuating lever, a retarding device connected with one end of the lever, a normally inoperative carrier mounted in coöperative relation with the receptacle, an actuating device for transmitting motion from said 85 lever to the carrier to actuate the latter, and a controlling device embodying an arm substantially concentric with said shaft and normally retaining the actuating devices and the carrier out of coöperative relation.

6. In a vending machine, the combination with a receptacle for the articles to be vended, 90 of an operating shaft carrying an actuating lever, a retarding device connected to one end of the lever, a normally inoperative carrier mounted in coöperative relation with the receptacle, a pawl carried by the lever and arranged to coöperate with a ratchet wheel connected with the carrier, and a controlling arm substantially concentric with said shaft and coöoperating with the pawl for disengaging it from the ratchet.

In testimony whereof, I have signed my name to this specification in the presence of two subscribing witnesses.

ISAAC H. GARSON.
